UNITED STATES PATENT OFFICE.

CARL G. THOMPSON, OF KNOXVILLE, TENNESSEE.

GRINDING-MILL.

1,392,464.

Specification of Letters Patent.

Patented Oct. 4, 1921.

Application filed October 30, 1920. Serial No. 420,666.

To all whom it may concern:

Be it known that I, CARL G. THOMPSON, a citizen of the United States, residing at Knoxville, in the county of Knox and State 5 of Tennessee, have invented certain new and useful Improvements in Grinding-Mills, of which the following is a specification.

This invention relates to mills provided with revoluble grinding heads and used 10 chiefly for grinding grain, such as wheat or corn; and it consists in the novel construction and combination of the parts herein- after fully described and claimed.

A mill constructed according to this invention may be used for grinding in the usual way, but it is specially adapted for re-grinding bran and other similar material, such as flour containing bran. The flaky nature of bran necessitates the employment 20 of feed passages of relatively large area and means for forcing the material under pressure in a continuous stream through the said passages, otherwise the mill will become clogged. The grinding heads must each be 25 revolved in the same direction, but at different speeds, and must be free to slide a little away from each other to permit any lumps to pass from between them.

In the drawings, Figure 1 is a front view, 30 partially in section, of the principal parts of a grinding mill constructed according to this invention. Fig. 2 is an end view of the grinding heads, the upper one-half of the high speed head being omitted to show the 35 grinding plates of the low speed head. Fig. 3 is a diagrammatic plan view of portions of the grinding heads and plates, partially in section on the line 3—3 in Fig. 2. Fig. 4 is a longitudinal section through the inlet 40 end portion of the feeding device.

Two grinding heads 6 and 7 are provided, and arranged inside a suitable casing 8 having an outlet 9 for the ground material at its lower part. The casing is secured on 45 a suitable base 10, to which also are secured shaft bearings 12, 14 and 15 of approved construction. The high speed grinding head 6 is secured on a shaft 16 which is journaled in the bearing 12, and provided 50 with a driving pulley 17. The shaft 16 has also another bearing, and means for adjusting the shaft longitudinally, but these parts are not shown as they are of any approved construction.

55 The low speed grinding head 7 is secured on a tubular shaft 18 which is journaled in

the bearings 14 and 15, and provided with a pulley 19 for revolving it. The tubular shaft 18 also serves as a feed passage for introducing the material to be ground between the grinding plates of the grinding heads.

The grinding heads are both revolved in the same direction, as indicated by the arrows in Figs. 2 and 3, the high speed head 6 having double arrows adjacent to it to indicate that it is driven at a greater speed than the head 7. The speeds are arranged and proportioned so as to give the best results from the differential action.

The grinding plates are secured to the respective heads by any suitable fastening devices, such as the screws 20. The grinding plates of the high speed head 6 preferably comprise an inner ring 21, and a series 75 of segmental plates 22 arranged around the inner ring in circular form. The inner ring 21 has a series of teeth 23 cut in its face by any suitable machine. These teeth are shaped like saw teeth in cross-section, and are arranged with their edges foremost in the direction of motion. These teeth 23 are arranged diagonally, and their inner end portions are arranged substantially at a tangent to the periphery of the driving 80 shaft 16, with their inner end portions in advance of their outer end portions in the direction of motion.

The outer plates 22 are each provided with furrows 25, and grooved or corrugated faces 90 26 arranged alternately of the furrows. The furrows 25 are triangular in cross-section, and their ends 27 are arranged rear-most and are slightly undercut. These furrows may be cut in the plates or cast in 95 them as found most desirable. The faces 26 and the furrows 25 are also arranged diagonally, or at a tangent to the shaft 16, similar to the teeth 23, and the fine diagonal corrugations are machine-cut. The faces 26 100 have their teeth or corrugations cut in them with a machine, and arranged tangentially of the shaft 16 of the grinding head. These corrugations may be rounded or they may be teeth similar to the teeth 23 in form or 105 cross-section, or they may be of other suitable form.

The grinding plates of the low speed head 7 preferably comprise an inner ring 31, and a series of segmental plates 32 similar to 110 the corresponding parts of the high speed head. The inner ring 31 has machine cut

- teeth 33 similar to the teeth 23, but arranged radially of the axis of the grinding head. As the opposed teeth 23 and 33 are arranged diagonally of each other and run point to point, their cutting edges have a slicing action on the material or grain which is fed between them. The teeth are made like saw teeth in cross-section so, that they will retain their sharp cutting edges as the plates 10 become worn away. The segmental plates 32 are provided with radial furrows 35 and radially grooved or corrugated faces 36, similar to the furrows 25 and faces 26 of the plates 24. The ends 37 of the furrows 15 35 are however arranged foremost in the direction of motion, so that they are overtaken by the ends 27, and the material or grain is operated on by the cutting edges of the said ends 27 and 37.
- 20 By using machine cut teeth and corrugations as hereinbefore described, and by revolving the grinding heads at differential speed in the same direction, the material or grain can be ground very fine. The grinding heads do not have to be revolved so fast as in the mills ordinarily constructed, and less power is required to revolve the grinding heads.
- 25 The material or grain is fed through the 30 tubular shaft 18 from a hopper 40 by means of a spiral conveyer 41. The hopper 40 has a conical chamber 42 at its lower part, which is secured to the bearing 15 or other stationary part of the mill. The conical chamber 42 is arranged in line with the tubular shaft, and the conveyer shaft has a conical end portion 43 which is arranged in the conical chamber 42 and provided with conveyer flights 44. The conveyer is revolved by any approved means, such as the 35 wheel 45. The conical part 43 and the conveyer flights on it operate as a force feeder and pack the material into the tubular shaft and prevent it from revolving with the 40

spiral conveyer without being moved longitudinally.

Instead of providing the conveyer with a driving wheel 45, its shaft can be connected with the shaft 16 of the high speed grinding head by a screwthreaded portion 46, or 50 other suitable coupling.

The bran, or other similar material is forced between the inner rings of the grinding heads, and the slicing action of the teeth reduces it to a preparatory fineness. 55 The material is then forced under pressure aided by centrifugal action into the furrows of the outer plates, and the grinding is completed by the fine corrugations, the furrows and fine corrugations of the high 60 speed head being arranged diagonally of the radial furrows and corrugations of the low speed head, and also operating with a slicing action upon the material.

What I claim is:

In a mill for re-grinding bran and other similar material, two horizontal driving shafts arranged end to end, one of the said shafts being tubular, means for revolving the said shafts at different speeds in the 70 same direction, opposed vertical grinding heads secured on the said shafts, metallic inner grinding rings secured to the said heads and provided with relatively coarse saw-shaped grinding teeth which 75 work point to point, metallic outer grinding rings encircling the inner grinding rings and provided with feed furrows and finely serrated grinding surfaces arranged alternately, and means for forcing the material 80 to be re-ground under pressure through the tubular shaft and between the inner grinding rings into the feed furrows of the outer grinding rings.

In testimony whereof I have affixed my 85 signature.

CARL G. THOMPSON
